GUY E. PARKER, OF BIRMINGHAM, MICHIGAN, ASSIGNOR TO GENERAL MOTORS CORPORATION, OF DETROIT, MICHIGAN, A CORPORATION OF DELAWARE

RUBBER ENGINE SUPPORT

Application filed January 4, 1929. Serial No. 330,382.

This invention relates to resilient supports and more particularly to an improvement in cushion mountings especially adapted for mounting an internal combustion engine in the chassis frame of a motor vehicle.

Practically every internal combustion engine has an inherent vibration caused by the unbalance of its various moving parts. These constantly occurring high frequency 10 and small amplitude vibrations when transmitted through the chassis frame result in the building up of vibratory periods, impose damaging strains on and induce sympathetic vibrations and noise in the various parts of 15 the vehicle and are also disagreeable to the human nervous system.

It is an object of the present invention to provide an improved mounting for insulating the engine from the frame and for absorbing or damping the inherent engine vibrations so that the disagreeable and harmful effects of vibrations are eliminated.

It is also an object of the invention to provide a mounting for cushioning shocks and 25 stresses in all directions whereby either horizontal or vertical vibrations are damped out, and the engine itself freed from strains incident to road shocks, frame weaving and the like.

Another object of the invention is to provide a simple and inexpensive structure 30 which will facilitate production assembly of vehicles and readily permit subsequent removal and replacement of the engine in the 35 chassis without disturbing the relation of the mounting parts.

Additional objects and advantages of the invention will be apparent from the following specification when taken in connection 40 with the accompanying drawing wherein Fig. 1 is a fragmentary top plan view of a chassis frame having an engine mounted therein in accordance with the present invention.

Fig. 2 is a side elevation of a portion of the chassis frame with parts broken away to show the support.

Fig. 3 is a vertical sectional view taken on 50 line 3-3 of Fig. 2 and Fig. 4 is a sectional

view of the chassis frame and a supporting bracket and is taken on line 4-4 of Fig 2.

In the drawings, illustrating the preferred embodiment of the invention, the numerals 1-1 indicate a pair of longitudinally extending channel shaped chassis frame members and 2 is an internal combustion engine to be supported in the frame. The engine shown in the drawings is of the V eight cylinder type, which consists of two banks or rows of four cylinders each, arranged at an angle to each other and having pistons connected to a common crankshaft, but it will be evident that other types of engines may be mounted in the chassis frame by means of the present invention. Any suitable form of mounting may be used at the front of the engine, and if desired this front mounting may be the same as that illustrated at the rear. Secured within the channel of each frame member 1 opposite the flywheel housing 3 is a bracket 4 consisting of a vertical web having a marginal flange 5 at its side, a top flange 6 riveted or otherwise secured to the top flange of the frame member and a bottom flange 7 secured as by riveting to the lower flange of the frame member. The bracket also has a lateral ear 8 which may be riveted to the vertical side wall of the frame member 1. Intermediate 55 60 65 70 75 80 85 90 95 100

its height the bracket 4 is provided with a semi-spherical portion 9 affording pocket or depression with which cooperates a similar pocket or depression formed in a cover or cap 10 removably secured by bolts 11 to bracket 4. Secured within the opening formed by the cooperating depressions, by means of the cap 10, is a spool or inner member 12 having an intermediate enlargement 13 and end flanges 14 and 15. The inner surfaces of the end flanges 14 and 15 taper outwardly and cooperate with beveled or inclined shoulders 16 at opposite ends of the opening through the outer member, comprising the bracket 4 and cap 10, to hold therebetween the outwardly flared portion of bushing 17 of L-shape in section and consisting of rubber or other similar elastic deformable material, the other portion of which bushing extends axially between adjacent surfaces of the inner and outer members and between an end flange 100

14—15 and the intermediate enlargement 13. Each bushing 17 at opposite ends of the parts is preferably formed in arcuate or half round sections (see Fig. 2) for convenience of assembly. A fastening bolt 18 secures the spool 12 to the flywheel housing 3, passing inwardly through an opening in the spool and having screw threaded engagement with the nut 19 located in a depression 10 in the inside wall of the flywheel housing and secured in place by a set screw 20. Aligned with the opening through the spool 12 is an opening 21 in the vertical web of the frame member and through which the head of the bolt 18 extends, the opening being sufficiently large to permit engagement with the bolt head of a spanner wrench or other tool for the manipulation of the bolt into and out of engagement with the nut 19. One or more shims such as indicated at 22 20 may be inserted between the flange 15 and flywheel housing 3 to properly locate the engine in the chassis frame.

After the bracket 4 is fastened to the frame member 1, the spool 12 and elastic bushings 17 are secured in place by the retainer cap 10, the bolts 11 being drawn up to place the elastic bushings under an initial predetermined pressure which materially increases the life of the rubber substance and also eliminates its excessive responsiveness to deformation. When the engine is to be mounted in the frame it is only necessary to swing it into proper position and insert the bolt 18 through the spool 12 and then turn the bolt into screw threaded engagement with the nut 19. Of course this procedure can be varied and if desired the spool can first be mounted on the flywheel housing and subsequently fastened 40 to the bracket. Should it later become necessary, after the vehicle has been in use, to remove the engine this may be done by simply unthreading the bolt 18 without disturbing the assembled unit or the relation of the inner 45 and outer members and the predetermined compression of the rubber bushings.

While only a preferred embodiment has been illustrated, it will be understood that the invention is not limited to the specific details 50 described, but that such modifications may be made as come within the scope of appended claims.

I claim:

1. A resilient mounting of the character 55 described, including in combination with a support and a body to be supported, of an outer member, consisting of a bracket fastened on the support and detachable cap secured on the bracket, the adjacent surfaces of the bracket and cap having cooperating depressions therein to afford an opening through the outer member, an inner member positioned within said opening and consisting of a spool-like element having an intermediate enlargement and an annular

flange at each end, a pair of elastic deformable bushings of substantially L-shape in section interposed between said members at each end and located between the end flange and enlargement on said inner member, and a connecting element passing through the inner member and detachably engageable with the body to be supported. 70

2. A resilient mounting of the character described, including in combination with a support and a body to be supported, of an outer member consisting of a bracket permanently fastened on the support, and a cap detachably secured to the bracket, the adjacent surfaces of the bracket and cap having cooperating depressions to afford an opening through the outer member, a spool-like inner member carried by the body to be supported and held within said opening by the attachment of said cap, and elastic deformable material arranged in substantially L-shape in section at one end, interposed between said inner and outer members. 75

3. A resilient mounting of the character described, including in combination with a support and a body to be supported, of an outer member consisting of a bracket permanently fastened on the support and a cap detachably secured to the bracket, the adjacent surfaces of the bracket and cap having cooperating depressions to afford an opening through the outer member, a spool-like inner member carried by the body to be supported and held within said opening by the attachment of said cap and elastic deformable bushings of substantially L-shape in section interposed between the inner and outer members adjacent their opposite ends. 80

4. A resilient mounting of the character described, including in combination with a support and a body to be supported, of an outer member consisting of a bracket permanently fastened on the support and a cap detachably secured to the bracket, the adjacent surfaces of the bracket and cap having cooperating depressions to afford an opening through the outer member, a spool-like inner member carried by the body to be supported and held within said opening by the attachment of said cap and elastic deformable bushings of substantially L-shape in section interposed between the inner and outer members adjacent their opposite ends, each of said bushings consisting of two or more arcuate sections. 100

5. A resilient mounting of the character described, including in combination with a support and a body to be supported, of a spool-like member projecting from the body, 125 an apertured bracket associated with the support thru which the spool-like member projects and which extends partly into the annular channel of the spool-like member, and elastic deformable material interposed be- 130

tween adjacent surfaces of the spool-like member and said bracket.

6. A resilient mounting of the character described including in combination with a support and a body to be supported, of an outer member consisting of a bracket carried by the support and a removable cap secured to the bracket and forming therewith an opening through the outer member, a spool-like inner member held within said opening by the attachment of said cap, resilient bushings of substantially L-shaped interposed between said members at opposite ends thereof, and means to detachably connect the inner member to the body to be supported.

10 7. A resilient mounting of the character described, including in combination with a support and a body to be supported, of a spool-like member projecting laterally from the body, resilient material positioned about said spool-like member and having angular portions that fit against the cylindrical portion and end flanges of said member, a bracket carried by the support and forming a seat for 20 said resilient material, and a removable retainer cap secured to the bracket for holding the parts in assembled relation.

25 8. The structure of claim 7 and a detachable connection between the spool-like member and the body, whereby the body and support may be separated without disturbing the assembled relation of the mounting parts.

30 9. A resilient mounting of the character described, including in combination with a support and a body to be supported, of a spool-like member projecting from the body and having a medial enlargement, elastic deformable bushings of substantially L-shape in section at each end of said member, each having portions thereof lying in contact with the adjacent end flange and with the peripheral surface of the member between the end flange and said medial enlargement, a member associated with said support having a cavity 35 40 45 therein into which said spool-like member projects and against which said bushings seat, and a retainer cap removably secured to said member to hold the parts in assembled relation.

50 10. A resilient mounting including in combination with a frame and an engine to be supported in the frame, of a bracket carried by a frame element on the inside thereof, a removable member secured to the bracket, a spool held by said member between the member and the bracket, a cushion interposed between the spool and bracket, and a fastening bolt passing inwardly through the spool and detachably engaging the engine, said frame element having an opening adjacent the spool to permit manipulation of said bolt.

55 60 65 11. A resilient mounting including in combination with a chassis frame and an engine to be supported in the frame, of a cushioning unit carried by the frame and including

inner and outer members and an intermediate cushion, a fastening bolt passing through an opening in the inner member and detachably engaging the engine, said frame having a portion thereof cut away in alignment with said opening in the inner member to permit manipulation of the fastening bolt.

70 12. A resilient mounting of the character described, including in combination with a support and a body to be supported, of a spool-like member projecting laterally from the body, resilient material positioned about said spool-like member and having angular portions that fit against the cylindrical portion and end flanges of said member, and means associated with the support providing a seat for said resilient material.

75 80 In testimony whereof I affix my signature.
GUY E. PARKER.
